Patented Aug. 7, 1928.

UNITED STATES PATENT OFFICE.

FRANK J. PETERSON, OF PITTSBURGH, PENNSYLVANIA

KNOB.

Application filed August 27, 1927. Serial No. 215,808.

This invention relates to a knob assembly, and is particularly applicable to a knob assembly such as a door-knob for a glass or other easily fractured knob.

5 Heretofore, glass knobs have been provided at their rear faces with an extension which is knurled or notched. On the shaft of the knob assembly there is a sleeve having projections which engage in the notches 10 or in the knurled surface of the knob to hold the knob against rotation with respect to the sleeve. The sleeve and the knob are connected by means of a thin sheet metal ferrule which is spun over a bead on the 15 knob. Such a construction, while being of neat appearance, will not stand up under usage for the reason that the thin metal ferrule is easily bent when the knob is pulled.

According to the present invention there 20 is provided an assembly which will form a much more secure connection between the knob and its mounting and wherein the ferrule will serve only to enclose the other parts of the knob and not be subject to mechanical 25 strains as it is in the present constructions.

My invention may be readily understood by reference to the accompanying drawings, in which—

Figure 1 is a vertical longitudinal section 30 through a portion of a knob assembly embodying my invention;

Figure 2 is a side elevation of the knob;

Figure 3 is a view of the rear face of the 35 knob;

Figure 4 is a perspective view of the sleeve on which the knob is carried; and

Figure 5 is a detail section on a scale larger than Figure 1 and at right angles thereto.

40 In the drawings, 2 designates a knob having an extension 3 at the back thereof with a bead 4 thereon. Formed in the end face 5 of the knob is a dovetail groove 6. As shown in Figure 3 the dovetail groove 6 is 45 slightly wider at one end than at the other to facilitate the formation of the knob in a press. Fitted into the dovetail slot 6 is the cross head 7 at the end of a sleeve 8. The cross head 7 has tapered sides to cooperate 50 with the dovetail groove 6 in the glass knob. The inside of the sleeve 8 is threaded, and screwed into the sleeve in the knob spindle 9. The knob spindle 9 passes all the way 55 through the sleeve, as clearly shown in Figure 5, and its end bears against the bottom of the groove 6. By turning the shaft 9

relatively to the sleeve 8, the knob 2 may be pushed away from the cross bar 7 to cause the sides of the cross bar to frictionally clamp the sides of the dovetail groove 6 and thereby firmly hold the knob on the cross bar.

55 Mounted on the sleeve 8 is a ferrule 10 of sheet metal. The outer portion 11 of this ferrule is spun over the bead 4 to enclose the connection between the sleeve and the knob. A set screw 12 passes through the ferrule and through the sleeve and bears against the shaft 9 for holding the parts in fixed relation.

70 The end face of the knob, including the bottom of the groove 6 may be suitably ornamented so as to show through the knob when it is assembled. For the purpose of increasing the ornamental effect, the end 75 face of the knob may be silvered or otherwise ornamented. The practice of silvering the end face of the knob is now resorted to. If desired, the face of the cross bar 7 may be suitably ornamented to show through 80 the knob.

An assembly embodying the present construction can be quickly put together. The strain on the knob is transmitted to the cross bar 7 without being transmitted through 85 the ferrule 10. Heretofore the ferrule has formed the only positive connection for holding the knob and the sleeve against strains in a direction longitudinally of the spindle 9 and the turned-over portion 11 of 90 the ferrule would bend out. With the present construction the longitudinal strains are absorbed in the cross bar 7 and the undercut or dovetail groove 6 in the knob and the ferrule forms only an enclosing shield.

95 While I have specifically shown and described a specific embodiment of my invention, it will be understood that various changes and modifications may be made in the construction thereof without departing 100 from my invention or the scope of the appended claims.

I claim:

1. A knob assembly comprising a knob having an undercut slot in the rear face 105 thereof, a sleeve having a cross bar engaging in said slot, and a shaft threaded through the sleeve and adapted to bear against the end face of the knob.

2. A knob assembly comprising a knob 110 having an undercut slot in the rear face thereof, a sleeve having a cross bar engaging

in said slot, a shaft threaded through the sleeve, and a ferrule enclosing the sleeve and embracing a portion of the knob and confining the knob against transverse sliding movement on the cross bar.

3. A knob assembly comprising a knob having a transversely extending dovetail groove in the rear face thereof, a sleeve having a cross bar thereon, said cross bar being shaped to cooperate with the dovetail groove of the knob and being entered in said groove, and a shaft threaded through the sleeve,
- 10 4. A knob assembly comprising a knob

having a rearwardly projecting extension with a bead thereon, said knob having a 15 transversely extending undercut groove on the rear face thereof, a sleeve having a cross bar thereon, which cross bar is engaged in said undercut groove, a ferrule enclosing the sleeve and embracing the bead, 20 and a shaft threaded through the sleeve with its end bearing against the end of the knob.

In testimony whereof I have hereunto set my hand.

FRANK J. PETERSON.
